ATTORNEYS

UNITED STATES PATENT OFFICE.

CLARENCE E. GILBERT, OF ABERDEEN, SOUTH DAKOTA.

SCARIFIER TOOTH.

Application filed November 8, 1924. Serial No. 748,659.

My invention relates to improvements in scarifier teeth and more particularly to that type of scarifier tooth which is intended for replacement and for regrinding when run down.

An object of my invention is to provide a scarifier tooth of the type described which is so constructed as to permit the reversing of the tooth in its shank, thereby presenting a fresh point which may be used until worn down.

A further object of my invention is to provide a scarifier tooth of the type described which is so constructed as to compel its proper placement in position in its shank for efficient operation.

A further object of my invention is to provide a scarifier tooth of the type described which is extremely light in weight, yet which is sufficiently rigid to withstand all of the strain to which it may be subjected.

A further object of my invention is to provide a scarifier tooth of the type described which is of peculiar structure and which has a shank with a receptacle conforming in contour to the contour of the tooth, thereby preventing introduction by an unauthorized manufacturer of makeshift teeth which would impair the successful operation of the scarifier upon which the teeth are used.

A further object of my invention is to provide a scarifier tooth of the type described that is simple in construction, that may be manufactured cheaply, and that is thoroughly practical commercially.

Other objects and advantages will appear in the following specification, and the novel features of the invention will be particularly pointed out in the appended claim.

My invention is illustrated in the accompanying drawings forming part of this application, in which

Figure 1 is a side elevation of an embodiment of my invention with a part of the shank in section, and

Figure 2 is a sectional view along the line 2-2 of Figure 1.

In carrying out my invention, I make use of a shank 1 having a tapering aperture 2 therethrough which is substantially X-shaped in cross section (see Figure 2). The axis of the aperture 2 is disposed at a predetermined angle from the body of the shank 1 and is approximately 120 degrees therefrom for ordinary use.

My improved scarifier tooth, (as reference to Figure 2 will show) consists of a hardened steel body portion 3 having integral vertically and horizontally extending ribs, thereby forming a tooth having parallel walls. The body portion is provided with ribs 4 and 5 having parallel walls extending substantially at right angles with the walls of the body portion. The outer edges of the walls of one of the ribs are tapered from a point at one side of the center portion of the tooth to one end 6, and the walls of the other rib are tapered from a point on the opposite side of the center of the tooth to the other end 6, whereby cutting edges are formed.

The side walls 7 of the X-shaped body member extend to the edges 6. Openings 8 are provided through the body member 3 adjacent each end thereof, through which a locking bolt 9 is projected when either of the openings 8 is in registration with the aligned openings 10 in opposite side walls of the aperture portion of the shank 1. The purpose of the bolt 9 is to prevent dislodgment of the tooth from the shank and to facilitate removal of the tooth by removal of the bolt.

From the foregoing description of the various parts of the device, the operation thereof may be readily understood. My improved scarifier tooth is disposed in the position shown in Figure 1, and after long and continued use, let us assume that the edge is worn down to the dotted line 11 (see Figure 1). When the edge has been worn to this condition, the entire tooth is removed from the shank 1 by withdrawal of the bolt 9 and the tooth is replaced with the tapered surface 4 at the bottom. Thus the tooth edge formed by actual wear is in the proper position for use. After the edge has been worn down again, the tooth is removed and reversed, so that that edge 6 which at the present time has been elevated and which extends through the opposite side of the aperture 2 is in position for engagement with the road or other surface to be worked.

One of the most important features of my improved scarifier tooth is that utmost rigidity is obtained with minimum weight, and that the tooth is at all times held in the proper position for use.

It is impossible for an unauthorized person to insert make-shift teeth in the shank 1 which would not perform efficiently since the

tooth must be constructed by special manufacturing and must conform with the contour of the aperture in the shank 1.

I claim:

- 5 A scarifier tooth comprising a body provided with parallel walls and ribs provided with parallel walls extending substantially at right angles therefrom, the outer walls of one of said ribs being tapered from a point

at one side of the central portion of the tooth 10 to the ends, the walls of the other rib being tapered from a point on the opposite side of the center of the tooth to the ends, whereby cutting edges are formed on each end and the horizontal ribs being extended from one 15 end of the tooth to the other.

CLARENCE E. GILBERT.
